To all whom it may concern:

Be it known that I, Elizabeth Nightingale Graham, a citizen of the United States of America, residing in New York city, county of New York, and State of New York, have invented a new, original, and ornamental Design for a Compact or Similar Article, of which the following is a specification, reference being had to the accompanying drawing, forming part thereof, wherein:

Figure 1 is a front elevational view of a compact showing my new design.

Figure 2 is a side elevational view, and

Figure 3 is a rear elevational view thereof.

The characteristic feature of my design resides in the specific floral decoration on the compact, as shown.

I claim:

The ornamental design for a compact or similar article, substantially as shown and described.
